mensions than the diameter of the shafts 44 and 46 to permit relative lateral movement of the rollers.

After the tape is applied to the slide, the slide is inserted between the rollers 40 and 42 and is forced downwardly until it engages the stop or bottom wall 34 of channel 30. The slide is inserted between the rollers in such position that one end of the slide engages wall 39 or 38 of the channel 30. This position is specifically shown in Figure 11.

The rollers 40 and 42 are spaced at least at one end thereof from the upright walls 36 or 38 as shown in Figure 11. This spacing of the ends of the rollers from the adjacent wall is maintained by provision of shoulders 45 and 47 respectively in shafts 44 and 46.

When the slide S is inserted between rollers 40 and 42 with one edge against side wall 38, as shown in Figure 11, a portion of the tape indicated at 54 is positioned between the ends of rollers 40 and 42 and the wall 38. The portion of the tape between the rollers 40 and 42 is pressed into engagement with the side surfaces of the slide, but the portion of the tape indicated at 54 remains extending generally perpendicular to the plane of the slide.

After this first side of the slide has the tape affixed thereto, the slide is removed and turned a quarter turn so that the edge of the slide that was against the wall 38 is in the lowermost position. This latter edge of the slide is then inserted downwardly between the rollers, and the adjacent edge upon which the tape has not been folded down is kept against wall 38. This puts the portion of the tape previously indicated at 54 between the rollers 40 and 42 and forms a neat fold at the corners of the slide with overlapping portions of the fold in adhesive engagement with each other. That portion 54 of the tape referred to above is folded under the portion that is folded upwardly from the second edge. The spacing of the ends of the rollers 40 and 42 from the corresponding wall 38 is substantially equal to the width of the tape that is folded over against one side of the slide.

This procedure is continued around the periphery of the slide forming neatly folded corners of the tape as illustrated in Figure 10. Obviously in connection with the final edge, the extremity thereof is disposed between the rollers because the entire tape can be folded up at that time.

The slotted openings 48 and 50 permit the rollers to be spread apart in response to insertion of the slide therebetween. The tension of the springs 52 causes the rollers to firmly engage the side surfaces of the slide for pressing the tape against the slide.

With respect to the spacing, referred to above, of the ends of the rollers 40 and 42 from the adjacent wall 38, the preferred spacing is approximately the width of the portion of the tape that is folded over against one of the sides of the slide. This preferred spacing would result in having equal overlapping portions at the fold.

In the modified form shown in Figure 5, a pair of rollers 56 are shown having shafts 58. These shafts 58 are fixed laterally with respect to each other. The rollers 56 are made of resilient material. This permits deformation of the rollers upon the insertion of a slide 60 therebetween. The resiliency of the material in rollers 56 causes the tape to be pressed firmly against the side of the slide in adhering relationship.

In the modification shown in Figure 6, one

roller 62 is simply rotatably journalled in the upright walls of channel 64. The second roller 66 is journalled by means of shaft 68 in slotted hole 70. This slotted hole extends generally upwardly at an angle with the horizontal. When there is no slide inserted between the rollers 62 and 66, the shaft 68 lies in the lower portion of the slotted hole 70 and the rollers 62 and 66 are closest to each other. When a slide 72 is inserted between rollers 62 and 66, the rollers 66 and shaft 68 are bodily displaced away from the roller 62, the shaft 68 moving diagonally upwardly in slotted hole 70, as shown in Figure 6. Such an arrangement provides for the spreading apart of the rollers and the force of gravity acting upon roller 66 biases the roller 66 towards the roller 62 to provide a force for pressing the tape into adhering engagement with the sides of the slide.

The modification shown in Figure 7 is somewhat similar to the modification shown in Figure 6 in that the shaft for one of the rollers is journalled in a slotted hole which extends diagonally upwards from the horizontal. In the modification shown in Figure 7, the shaft for the other roller is journalled in a horizontally elongated slot which provides for initial variable spacing between the pair of rollers. This is primarily to accommodate greater variations in the thicknesses of photographic slides.

As shown in Figure 7, the roller 74 has a shaft 76 positioned in a horizontally elongated slot 78 in the upright walls of channel 80. The roller 82 has a shaft 84 positioned in an elongated slot 86 extending diagonally upward from the horizontal. A pair of ears 88 are welded, or in any other similar manner secured, to the outer sides of the upright walls of channel 80. Bolts 90 are threaded through ears 88 and are adapted to engage shaft 76 so as to limit the movement of shaft 76 to the left, as shown in Figure 7, upon the insertion of the slide 92 between rollers 74 and 82. By adjusting the position of bolts 90, the degree of spreading between rollers 74 and 82, to accommodate different thicknesses of photographic slides, may be varied.

While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What I claim as new and desire to secure by Letters Patent of the United States is:

1. In a device for applying adhesive tape to the sides and edges of a photographic slide, which tape is initially adhered to the edges of the slide and disposed generally in planes perpendicular to the plane of the slide, whereupon it is desired to fold the edges of the tape into adhering engagement with the side surfaces of the slide, the combination comprising a frame having a pair of spaced mounting flanges, a pair of elongated, cylindrical rollers disposed in parallel relation to each other between said mounting flanges, a roller shaft for each roller, said rollers being of greater length than the length of the longest edge of a slide, whereby the entire length of any edge of the slide may be thrust between the rollers and the edges of the tape along said edge of the slide may be rolled into engagement with the side surfaces of the slide, said rollers being rotatable inde-

pendently of each other, said mounting flanges having journal apertures therein within which are journalled the roller shafts, the journal apertures for at least one of said roller shafts being elongated to provide for lateral movement of one roller with respect to the other roller upon insertion of the slide therebetween, and said elongated apertures being so disposed that for every position of said one roller shaft along the length of said elongated journal apertures there is a different lateral spacing of the one roller from the other roller.

2. A device as set forth in claim 1 including means biasing the one roller journalled in said elongated journal apertures toward the other roller.

3. A device as set forth in claim 1 including spring means biasing the rollers toward each other.

4. A device as set forth in claim 1 wherein said elongated journal apertures extend diagonally upwardly from the horizontal, and gravity serving to bias the roller which is journalled in said elongated journal apertures toward the other roller.

5. A device as described in claim 1 wherein the journal apertures for both of said roller shafts are elongated, and the elongated journal apertures for at least one of the roller shafts extends diagonally upwardly from the horizontal.

6. A device as described in claim 1 wherein the journal apertures for both of the roller shafts are elongated, the elongated journal apertures for one roller shaft extending diagonally upwardly from the horizontal, the elongated journal apertures for the second roller shaft extending horizontally, and stop means on the frame for engaging the second roller shaft to limit the lateral movement of said second roller shaft at selective positions intermediate the lateral ends of its elongated journal apertures, whereby the initial spacing between the rollers may be varied.

7. In a device for applying adhesive tape to the sides and edges of a photographic slide, which tape is initially adhered to the edges of the slide and disposed generally in planes perpendicular to the plane of the slide, whereupon it is desired to fold the edges of the tape into adhering engagement with the side surfaces of the slide, the combination comprising a frame having a pair of spaced mounting flanges, a pair of elongated, cylindrical, rollers disposed in parallel relation to each other between said mounting flanges, a roller shaft for each roller, said rollers being of greater length than the length of the longest edge of a slide, whereby the entire length of any edge of the slide may be thrust between the rollers and the edges of the tape along said edge of the slide may be rolled into engagement with the side surfaces of the slide, said rollers being rotatable independently of each other, said mounting flanges having journal apertures therein within which are journalled the roller shafts, the journal apertures for at least one of said roller shafts being elongated to provide for lateral movement of one roller with respect to the other roller upon insertion of the slide therebetween, said elongated journal apertures being so disposed that for every position of the roller shaft along the length of said elongated apertures there is a different lateral spacing of that roller from the other roller, and a pair of springs connecting the corresponding ends of

70

75

said pair of roller shafts, whereby said rollers are biased toward each other.

8. In a device for applying adhesive tape to the sides and edges of a photographic slide, which tape is initially adhered to the edges of the slide and disposed generally in planes perpendicular to the plane of the slide, whereupon it is desired to fold the edges of the tape into adhering engagement with the side surfaces of the slide, the combination comprising a frame having a pair of spaced mounting flanges, a pair of elongated, cylindrical, rollers disposed in parallel relation to each other between said mounting flanges, a roller shaft for each roller, said rollers being of greater length than the length of the longest edge of a slide, whereby the entire length of any edge of the slide may be thrust between the rollers and the edges of the tape along said edge of the slide may be rolled into engagement with the side surfaces of the slide, said rollers being rotatable independently of each other, said mounting flanges having journal apertures therein within which are journalled the roller shafts, the journal apertures for at least one of said roller shafts being elongated horizontally to provide for lateral movement of the one roller with respect to the other roller, and adjustable stop means on said frame for engaging the roller shaft to limit the lateral movement of said roller shaft to selected positions intermediate the lateral ends of the elongated journal apertures, whereby the spacing between said rollers may be varied.

9. In a device for applying adhesive tape to the sides and edges of a photographic slide, which tape is initially adhered to the edges of the slide and disposed generally in planes perpendicular to the plane of the slide, whereupon it is desired to fold the edges of the tape into adhering engagement with the side surfaces of the slide, the combination comprising a frame having a pair of spaced mounting flanges, a pair of elongated, cylindrical, rollers disposed in parallel relation to each other between said mounting flanges, a roller shaft for each roller, said rollers being of greater length than the length of the longest edge of a slide, whereby the entire length of any edge of the slide may be thrust between the rollers and the edges of the tape along said edge of the slide may be rolled into engagement with the side surfaces of the slide, said mounting flanges having means spacing the axial ends of said rollers from at least one of said mounting flanges, spacing between said ends of the rollers and said mounting flange being substantially equal to the width of the tape that is folded over against one side of the slide, and said flange serving as a guide for an edge of the slide during the tape-folding operation.
